UNITED STATES PATENT OFFICE.

FREDERIC G. ROGERS, OF MILES, TEXAS.

HARNESS-LOOP.

No. 800,400.

Specification of Letters Patent.

Patented Sept. 26, 1905.

Application filed May 29, 1905. Serial No. 262,862.

To all whom it may concern:

Be it known that I, FREDERIC G. ROGERS, a citizen of the United States, residing at Miles, in the county of Runnels and State of Texas, have invented a new and useful Harness-Loop, of which the following is a specification.

This invention relates to harness-loops or billet-loops for receiving and retaining the free ends of straps, billets, and the like.

Ordinarily harness and billet loops are first folded or bent into shape and then stitched to a strap, the stitching being performed by hand, for the reason that machine-stitching is impossible on account of the loop being in the path of the needle. Having appreciated this difficulty, I propose to overcome the same by the production of a new and novel form of billet-loop which is capable of being opened out to permit machine-stitching of the same to a strap and afterward adjusted to complete the loop in a very simple, expeditious, and inexpensive manner.

With this object in view the present invention consists in the combination and arrangement of parts, as will be hereinafter more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the accompanying drawings, Figure 1 is a perspective view of a harness-loop having the loop of the present invention applied thereto. Fig. 2 is an enlarged sectional view taken through the loop in substantial parallelism with the strap. Fig. 3 is an enlarged cross-sectional view. Fig. 4 is a detail sectional view on the line 4-4 of Fig. 3. Fig. 5 is a detail view showing a modified arrangement of the invention.

In carrying out the present invention it is proposed to have the loop made up of a leather part to be stitched to a strap and metal parts carried by the ends of the leather part and capable of being interengaged to complete the loop. The leather or flexible part 1 is in the nature of a web or strap of suitable width and length, and the metal parts 2 and 3 are in the nature of angle-irons or arches, which are connected in any suitable manner to the ends of the web 1—as, for

instance, by rivets 4. The free end of the member 2 is notched or recessed in the top thereof, as indicated at 5, so as to form a seat for the tongue portion 6 of the free end of the other member 3, said tongue being produced by a transverse notch or recess 7 in the under or inner side of the member 3. In the seat 5 of the member 2 there is a socket 8, constituting a keeper for the reception of the free headed end of spring-latch 9, suitably secured within a bifurcation 10 in the tongue 6.

To attach the present loop, as shown in Figs. 1, 2, and 3, the flexible web 1 is placed transversely between the plies or layers 11 and 12 of the strap with the metal parts 2 and 3 detached and separated, so as to have the strap unobstructed to permit of the longitudinal rows of stitches 13, which are employed to connect the plies of the strap, being sewed through the web 1 without stopping or otherwise interrupting the operation of the machine employed for stitching the plies or layers of the strap. It is preferred to have each longitudinal edge of the ply or layer 11 of the strap notched or cut away, as at 14, to receive the web 1, so that when the metallic members 2 and 3 are swung inwardly toward one another to snap the spring-catch 9 into engagement with the keeper 8, so as to complete the loop, the bent end portions of the web 1 may come into the notches or cut-away portions, so as to avoid projections at opposite edges of the strap.

Besides enabling the loop to be machine-stitched to the strap the separable feature of the members 2 and 3 permits of the latter being engaged across the intermediate portion of a loose strap from opposite edges thereof when it is impossible or undesirable to run the free end of the strap through the loop.

When applying the loop to a single-ply strap 15, as shown in Fig. 5, the web 1 is applied across one face of the strap and secured thereto by means of two rows of stitches 16, and the members 2 and 3 are engaged across the opposite side of the strap in order that the interior of the loop may not be obstructed by the web 1.

From the foregoing description it will be understood that the loop of the present invention is entirely complete in itself and may be very conveniently stitched by machine to a strap without preparing the latter.

Having fully described the invention, what is claimed is—

1. A harness-loop comprising an attach-

ing-base, side members carried by the ends of the base and capable of being folded inwardly to arch across the same, the free ends of the side members being notched to fit flush when 5 in engagement, a keeper carried by one of the members, and a spring-latch carried by the other member for engagement with the keeper to connect the members.

2. A harness-loop comprising a penetrable 10 flexible base, metallic side members carried by opposite ends of the base and capable of being folded inwardly to arch across the same, and means to connect the side members to complete the loop.
- 15 3. A harness-loop comprising a flexible penetrable base, metallic side members connected to the ends of the base and capable of being folded inwardly into mutual engagement to arch across the base and complete 20 the loop, and spring locking means carried by the side members and capable of snapping into engagement when the side members are brought into engagement.

4. A harness-loop comprising a flexible penetrable base, metallic angle members having 25 corresponding ends secured to the respective ends of the base and capable of being folded inwardly across the base to bring their other ends into mutual engagement, the free end of one of the angle members being 30 notched and provided in its notched portion with a socket, the free end of the other member being notched and bifurcated to fit in the notched portion of the first-mentioned member, and a spring-latch mounted in the bifurcated portion of said other member and capable of engagement with the socket of the first-mentioned member when the two members are brought into engagement.

In testimony that I claim the foregoing as 40 my own I have hereto affixed my signature in the presence of two witnesses.

FREDERIC G. ROGERS.
